UNITED STATES PATENT OFFICE.

ALFRED D. TAYLOR, OF ATHOL, MASSACHUSETTS.

SANITARY DRINKING-FOUNTAIN.

1,207,661.

Specification of Letters Patent.

Patented Dec. 5, 1916.

Application filed March 25, 1916. Serial No. 86,629.

To all whom it may concern:

Be it known that I, ALFRED D. TAYLOR, a citizen of the United States, residing at Athol, in the county of Worcester and State of Massachusetts, have invented new and useful Improvements in Sanitary Drinking-Fountains, of which the following is a specification.

This invention relates to new and useful 10 improvements in drinking fountains.

The chief characteristic of this invention resides in the provision of the device of this character having a plurality of nozzles, the mouths of which are directed to a common 15 point whereby the streams ejecting from the nozzles will intersect each other to form a vertical stream from which a person may drink without the liability of becoming infected.

Another important characteristic of this 20 invention is to provide a device of this character having means for adjusting the nozzles to vary the inclination of the streams whereby the height of the vertical stream 25 will be varied accordingly.

Another important characteristic of this 30 invention resides in the provision of a device of this character having means for controlling the flow of water through each of the nozzles and independently of each other.

Other characteristics will appear as the 35 specification is read in connection with the accompanying drawings in which:—

Figure 1 is a top-plan view of the fountain 40 constructed in accordance with my invention. Fig. 2 is a bottom plan view. Fig. 3 is a central vertical section. Fig. 4 is a detailed view of the nozzle taken through one corner of the basin.

Referring to the drawings in detail, 1 45 designates a basin formed of any suitable material and which is preferably rectangular in formation. Arranged upon the underside of the basin is the supply pipe 2

50 which has a portion thereof extending downwardly from the basin, while the remaining portion lies parallel to the under side of the basin as at 3. This short section 3 of the supply pipe 2 is provided with branch pipes 4 which extend at right angles in opposite directions and in the same plane with the supply pipe. These branch pipes 4 have a combined length equal to the width of the basin and are provided at their free

extremities with a second pair of branch 55 pipes 5, the branch pipes 5 extending at right angles in opposite directions to underlie the marginal edge of the basin as is clearly shown in the drawings. The outer ends of the branch pipes 5 are upturned as 60 at 6 to conform to the outer face of the basin and are then bent inwardly as at 7. The inwardly bent terminals 7 are adapted to extend to rectangular openings 8 formed in the side walls of the basin at the corners 65 thereof and at a point above the bottom of the basin. The inwardly bent terminals 7 are formed to receive the threaded neck of a socket 9 the socket being of any ordinary construction but preferably spherical in 70 form and receiving a spherical extremity 10 of a nozzle 11. The socket 9 may be formed of sections so that the spherical extremity of the nozzle may be locked in adjusted position within the socket as will be understood.

From this construction it will be seen that the nozzles are arranged at the corners of the basin, and being adjustably mounted upon the terminals 7 of the branch pipes 5 80 they may be adjusted as to direct the streams of water to a point centrally of the basin. Assuming that each of the nozzles are emitting the streams of water toward the center of the basin, and that each stream 85 is at a slight upward inclination, it will thus follow that a vertical stream will be formed at the point of intersection of the four streams. Now by varying the inclination of the respective streams by means of adjusting the nozzles in various inclinations with relation to each other, the height of the vertical stream will be varied accordingly. In other words, if the various streams are inclined upwardly at a given 95 angle as to cause the streams to intersect each other to form a vertical stream, the height of the vertical stream will be lengthened in proportion to the angles of the streams.

In practice it has been found that there is a slight variation in the flow of water from the respective nozzles thereby causing an irregular vertical stream at the common point of intersection, therefore I have provided each of the branch pipes 5 with hand valves 12 whereby the flow of water through each of the nozzles may be regulated inde-

100

105

pendently of each other so that respective streams will have an equal amount of pressure to provide a steady vertical stream.

The horizontal portion 3 of the supply pipe 2 is provided with a valve 13, the stem of which extends through and beyond the vertical side of the basin as at 14. Surrounding the stem is a coil spring 15 which is adapted to normally close the valve and retain the stem in projected position on the basin, whereby, upon depressing of the stem the valve will be opened as will be understood. From this construction it will be seen that the water will only be flowing when the valve stem is depressed and upon relieving the stem of pressure the supply of water will be automatically cut off.

When it is desired to shut the supply of water off entirely, I have provided a horizontal portion 3 of the supply pipe with a hand valve 16 of any suitable construction, the same being operable from the under side of the basin as is shown in the drawings.

The bottom wall of the basin is provided with a drain outlet 17 which is preferably located at the opposite side of the bottom from that of the supply pipe, and communicates with the usual drain pipe 18, the pipe being formed with the usual trap 19.

Although I have described a specific means for mounting and adjusting the nozzles and have specifically stated the relative positions of the nozzles, I wish it to be clearly understood that I do not confine myself to the limitations described as I consider it within the scope of the invention to construct and arrange the nozzles in any manner to produce the result desired.

It is thought from the foregoing taken in connection with the accompanying drawings, that the construction and operation of this device will be apparent to those skilled in the art without further description, and that minor changes in the size, shape and

minor details of construction may be made 45 without departing from the spirit and scope of the appended claims.

What I claim is:—

1. A drinking fountain comprising a basin, a supply pipe, branch pipes formed in 50 said supply pipe, discharge nozzles mounted on each of said branch pipes and disposed at remote points upon said basin, said nozzles being arranged to direct their respective streams of water to a common point above 55 the basin to form a vertical stream, means for adjusting the nozzles to vary the inclination of the streams, and valves mounted in each of the branch pipes for controlling the flow of water independently of each 60 other.

2. A drinking fountain comprising a basin, a supply pipe, a plurality of discharge nozzles mounted upon the supply pipe and arranged to direct their respective streams 65 of water to a common point above the basin to form a vertical stream, and means for adjusting the nozzles to vary the height of the vertical stream.

3. A drinking fountain comprising a basin, a supply pipe, branch pipes formed in 70 said supply pipe, discharge nozzles mounted on each of said branch pipes and disposed at remote points upon said basin to direct their streams of water to a common point 75 above the basin to form a vertical stream, means for adjusting the nozzles to vary the inclination of the stream, valves mounted in each of the branch pipes for controlling the flow of water independently of each 80 other, and a valve within said supply pipe and controllable from the top of the basin.

In testimony whereof I affix my signature in presence of two witnesses.

ALFRED D. TAYLOR.
